UNITED STATES PATENT OFFICE.

ALEXANDER A. LA VIGNE, OF CLEVELAND, OHIO, ASSIGNOR OF ONE-HALF
TO HENRY F. MILLER, OF SAME PLACE.

DESIGN FOR A WATER-HOLDER.

SPECIFICATION forming part of Design No. 32,787, dated June 5, 1900.

Application filed April 19, 1900. Serial No. 13,549. Term of patent 14 years.

To all whom it may concern:

Be it known that I, ALEXANDER A. LA VIGNE, a citizen of the United States of America, and a resident of Cleveland, in the county of Cuyahoga and State of Ohio, have invented and produced a new and original Design for Water-Holders, of which the following is a specification, reference being had to the accompanying drawings, forming a part thereof.

- 10 This design relates to receptacles for holding liquids, especially of the character used in therapeutics for holding water in proximity to the human body in order to raise or lower the temperature of certain portions thereof.
- 15 The leading feature of my design consists of an elliptical-shaped shallow vessel having curved surfaces and rounded sides conforming to and resembling the curvature of portions of the surface of the human body.
- 20 Referring to the drawings, Figure I is a view showing my design in perspective. Fig. II is a view showing my design in side elevation.
- 25 Referring to the drawings, *a* represents the upper surface of my water-holder. This surface is convex in its general effect. This surface near the central portion *a'* is substantially flat and then curves down to the sides and ends. The curvature of the portions of
- 30 the surface near the ends, as at *a³a³*, is much greater than the curvature of the portions of the surface near the sides, as at *a²a²*.

b represents the lower surface of the vessel. This surface is similar in general outline and curvature to an elliptical-shaped section taken from the surface of a cylinder—that is, the surface is flat in the direction of its shorter axis and concave in the direction of its longer axis.

Near the center of the surface the portion *b'* is substantially flat for a distance in both directions.

The receptacle is deepest at its central portion and is quite shallow toward the edges, where the upper and lower surfaces meet at an acute angle.

The edges of the receptacle, where the upper and lower surfaces meet, are curved and rounded, so that the receptacle is elliptical shape in plan.

Having described my invention, what I claim as new, and desire to secure by Letters Patent, is—

The design for a water-holder, as herein shown and described.

Signed by me at Cleveland, Ohio, this 12th day of April, 1900.

ALEXANDER A. LA VIGNE.
